CLAIM

The ornamental design for an image inputting device, as shown and described.

DESCRIPTION

FIG. 1 is a front view of an image inputting device showing our new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The cable shown in FIGS. 1, 2, 5, 6 and 7 is broken away to indicate the indeterminate length.
